CLAIM

(51) **LOC (10) Cl.** **13-01**

I claim the ornamental design for a wind turbine with a unibody up-tilt furling, as shown and described.

(52) **U.S. Cl.**

DESCRIPTION

USPC **D13/115**

FIG. 1 is a bottom perspective view of a wind turbine with a unibody up-tilt furling showing my new design, in use condition;

(58) **Field of Classification Search**

FIG. 2 is a bottom perspective view thereof;

USPC D13/115; D21/455, 458; 290/55;

FIG. 3 is a front elevational view of FIG. 2;

415/4.1, 4.2

FIG. 4 is a rear elevational view of FIG. 2;

CPC F03D 7/0208; F03D 3/002; F03B 13/00;

FIG. 5 is a right-side elevational view of FIG. 2;

F03B 1/00; F05B 2240/21; F05B

FIG. 6 is a left-side elevational view of FIG. 2;

2240/221

FIG. 7 is a top plan view of FIG. 2;

See application file for complete search history.

FIG. 8 is a bottom plan view of FIG. 2; and,

(56) **References Cited**

FIG. 9 is a top perspective view thereof, illustrated in a tilted-up position.

U.S. PATENT DOCUMENTS

The broken line in the figure drawings is included for the purpose of illustrating unclaimed environment and forms no part of the claimed design.
